UNITED STATES PATENT OFFICE.

EDWARD P. REILLEY, OF CLEVELAND, OHIO.

VAPOR FEED FOR CARBURETORS.

1,409,313.

Specification of Letters Patent. Patented Mar. 14, 1922.

Application filed September 8, 1917. Serial No. 190,384.

To all whom it may concern:

Be it known that I, EDWARD P. REILLEY, a citizen of the United States, and resident of Cleveland, in the county of Cuyahoga and 5 State of Ohio, have invented certain new and useful Improvements in Vapor Feed for Carburetors, of which I hereby declare the following to be a full, clear, and exact description, such as will enable others 10 skilled in the art to which it appertains to make and use the same.

The objects of the invention are to provide means for drawing air, charged with vapor, into the mixing chamber of the carburetor of an explosive engine, whereby a 15 number of advantageous results are obtained.

The addition of the water vapor in a superheated form, when it is commingled 20 with the vapor of gasoline, does not interfere with the power of the explosion, and tends to prevent the deposit of carbon as a hard substance upon the sides of the cylinder. It also prevents a previously formed 25 carbon deposit from becoming incandescent, and causing the premature firing of the charge.

The vaporized water is applied to the air 30 inlet passage of the carburetor, instead of to the intake pipe between the carburetor and cylinders, thus improving the mixture by previous comingling in the carburetor, and also preventing the loss of vacuum when the inlet pipe becomes accidentally broken. 35 The employment of this additional amount of vapor adds greatly to the efficiency of the motor, in making it run more smoothly, and in the increase of power obtained. It also reduces the amount of valve grinding 40 required and the amount of frictional resistance throughout the engine.

The invention comprises, a pipe or passage 45 for directing the vapor accumulated in the top of the radiator into the air inlet opening of the carburetor and trapping coils in the pipe which encircle the exhaust and serve as heating coils which deliver the vapor to the carburetor in a superheated state.

It also comprises a valve float in the top 50 of the radiator by means of which cold water is prevented from entering the vapor feed pipe, when its level is raised above the inlet opening leading thereto.

The invention further includes the combination and arrangement of parts and construction of details, hereinafter described,

shown in the accompanying drawings and specifically pointed out in the claims.

In the accompanying drawings, Fig. 1 is a side elevation of an automobile engine, 60 showing the radiator and cylinders and carburetor, and showing the vapor feed pipe entering the air inlet to the carburetor, and coiled about the exhaust pipe.

Fig. 2 is an enlarged vertical section of the 65 top of the radiator, showing the upper ends of the overflow pipe and vapor feed pipe and the float valve which alternately opens and closes the inlet openings leading thereto.

Fig. 3 is a plan view thereof. 70

In these views A represents the radiator. B the cylinders. C the exhaust pipe. D the carburetor. E the air inlet passage leading to the carburetor. F is the overflow pipe in the radiator. G is the divided vapor feed 75 pipe the engine and radiator extremities of which are connected by means of a flexible tube G', shown in Fig. 1, leading from the top of the radiator, where vapor quickly accumulates as soon as the engine becomes 80 heated, and heats the water in the jackets encircling the cylinders, the heated water flowing through the pipes H. The return is not shown since it is well known in common use. I is a coil upon the feed pipe 85 which encircles the exhaust pipe C, and finally enters the air inlet passage leading to the mixing chamber. In some engines the coil can not be made to encircle the exhaust pipe and hence can be coiled on top thereof. 90

The vapor feed pipe is provided with an inlet opening J at its upper extremity and at its lower extremity is provided with an outlet opening K which projects preferably, 95 axially of the air inlet pipe E. The force of the vacuum which draws in the air and gasoline vapor into the carburetor will also draw the water vapor into the carburetor. A certain amount of steam pressure will also accumulate in the intake source since each 100 pipe is closed at its upper end.

The vapor feed pipe is coiled about the exhaust pipe at I so as to absorb the heat therefrom, which quickly superheats the vapor in the feed pipe since the coil is 105 closely applied thereto. This coil serves also as a trap in which the vapor when condensed accumulates to prevent water from entering the carburetor. The valve M is a float and rises when the water level in the 110 radiator rises and cuts off the inlet opening J in the vapor feed pipe, and simultaneously

uncovers the outlet opening P, leading to the overflow thus permitting the excess of water to escape. Sleeves N, O on the float permit adjustment of the respective over-flow levels. When the float falls, it uncovers the opening in the vapor feed pipe and covers the opening in the overflow pipe.

Having described the invention what I claim as new and desire to secure by Letters

10 Patent is:

1. In an explosion engine, provided with cylinders, a circulating water passage, and a radiator, and an exhaust pipe, and carburetor, the combination therewith, of a feed pipe leading from the upper end of said radiator to said carburetor, said feed pipe having an opening above the normal level of water in said radiator, and a float valve in said radiator for closing said opening in said feed pipe when the water level rises above the normal.

2. In combination with the radiator and carburetor of an explosion engine, a feed pipe for water vapor connecting the upper end of said radiator with said carburetor, an overflow pipe in said radiator, and a float valve adapted to alternately open and close the entrance to said feed and overflow pipes.

30 3. In an explosion engine, a radiator and a

carburetor therefor, said carburetor provided with an air admission passage, a water vapor feed pipe connecting the upper end of said radiator with said air admission passage, an overflow pipe in said radiator, said feed and overflow pipes having lateral openings, a float in said radiator having adjustable sleeves through which said pipes pass, said float serving to alternately cover and uncover said lateral openings.

4. In an explosion engine having a radiator, an exhaust pipe and a carburetor, said carburetor having an air inlet passage, a feed pipe leading from said radiator above water level to said air inlet passage in said carburetor, a coil in said pipe encircling said exhaust pipe and a flexible connection in said feed pipe, an outlet pipe in said radiator, and an automatically acting float valve for simultaneously opening the entrance to said feed pipe and closing the entrance to said overflow pipe and alternately therewith, closing the entrance to said feed pipe and opening the entrance to said overflow pipe.

In testimony whereof, I hereunto set my hand this 11th day of August 1917.

EDWARD P. REILLEY.
